DESIGN FOR ALPHABET

Laszlo B. Biro, Jamaica, N. Y.

Application October 22, 1937, Serial No. 72,364

Term of patent 3½ years

To all whom it may concern:

Be it known that Laszlo B. Biro, a citizen of United States and resident of Jamaica, in the county of Queens, State of New York, has invented a new, original, and ornamental Design for Alphabet, of which the following is a specification, reference being had to the accompanying drawing, forming part thereof, and in which,

The single figure of the drawing illustrates an alphabet embodying the design.

I claim:

The ornamental design for alphabet, substantially as shown.

LASZLO B. BIRO.
